UNITED STATES PATENT OFFICE.

WALTER D. GILES, OF LEESVILLE, LOUISIANA.

COUPLING FOR WELL RODS.

Application filed April 3, 1923. Serial No. 629,645.

To all whom it may concern:

Be it known that I, WALTER D. GILES, a citizen of the United States, residing at Leesville, in the parish of Vernon and State 5 of Louisiana, have invented certain new and useful Improvements in a Coupling for Well Rods, of which the following is a specification.

The present invention relates to a coupling for well rods and has for its principal object to provide means disposed between the walking beam and the polished rod so as to prevent the undesirable friction on the rods which causes crystallization thereof.

I have found from experience that the crystallization of the rods is caused by the heat imparted thereto during operation. It is now the practice to use rods twenty-five 20 feet long and three-quarters of an inch in diameter which are rather elastic. They usually work in a three inch pipe at a depth of four hundred to four thousand feet having from thirty to one hundred and 25 thirty connections. The weight lifted by the rods varies between four thousand to ten thousand pounds. In taking out these rods they are roughly handled and sometimes bent. When the rods are put back in 30 the well with possibly some bent, during the up and down motion these rods will rub against the tubing causing friction that produces heat. Salt water being in the well with the rods causes them to temper until 35 eventually they crystallize. Another important factor which must be taken care of is the tendency of the rods to rotate due to friction. The top rod which is known as the polished rod works through a stuffing 40 box at the top of the tubing and will not allow the rods to rotate. This produces heat aiding crystallization sufficiently that when a sudden turn is brought to bear against the rods they snap. The purpose of this 45 invention is to overcome these difficulties so as to greatly lengthen the life of the rods and to increase the efficiency of their operation.

With the above and numerous other objects in view as will appear as the description progresses, the invention resides in certain novel features of construction, and in the combination and arrangement of parts

as will be hereinafter more fully described and claimed.

In the drawing—

Figure 1 is an elevation of the coupling,

Figure 2 is an edge elevation thereof,

Figure 3 is a top plan thereof,

Figure 4 is a horizontal section taken 30 therethrough substantially on the line 4—4 of Figure 1, and

Figure 5 is a perspective view showing various elements forming parts of the coupling, said elements being disassembled.

Referring to the drawing in detail it will be seen that 1 designates the walking beam which is of conventional construction and 2 the polished rod which is also of conventional construction. In order to connect the 70 walking beam with the polished rod I provide a coupling consisting of the upper bar 3 and the lower bar 4 connected by the cables 5. The bars 3 and 4 and cables 5 are preferably formed of steel. The bar 3 is constructed with a central bore 6 and the end bores 7. The end bores 7 receive the steel cables 5 which are locked in place by screws 8. The bar 4 is provided with a central bore 9 and end bores 10. The end bores 10 receive the steel cables 5 which are locked in place by the screws 11. The polished rod 2 is projected through the bore 9 and a spherical block 13 having a diametrically disposed bore 14 is positioned 75 on the upper end of the rod 2 above the bar 4 and locked to the rod by means of a screw 15.

A stud 16 is constructed with a tapered body 17 having a threaded shank 18 at one 90 end and a shank 19 at its other end which terminates in the oppositely disposed apertured shoulders 20. The tapered body 17 is disposed in the bore 6 of the bar 3 and a spherical block 21 is threaded on the shank 18, a wrench grip extension 22 being provided so that it may be easily engaged therewith. A transverse aperture 22' is provided in the block 21 adapted to register with the transverse aperture 23 in the shank 18 so that a cotter pin 24 may be inserted therethrough for locking the block against rotation on the shank 18. The aperture shoulders 20 receive the ends of the cable 26 which passes around the walking beam 1.

With this device as the sole connection from the polished rod to the walking beam practically all friction in operation is overcome and allows the rods to be disposed 5 perpendicularly and in straight alignment with the well casing so that they will function properly.

I have, in the present instance, shown and described the preferred embodiment of 10 the invention which will give in practice satisfactory and reliable results, and it is to be understood that the same is susceptible of modification in various particulars without departing from the spirit or scope 15 of the invention or sacrificing any of its advantages.

Having thus described my invention what I claim as new is:—

1. A device of the class described including an upper bar and a lower bar, 20 flexible means connecting the upper bar with the lower bar, means for engaging the lower bar with a polished rod, a stud

loosely mounted in the upper rod, a cable attached to the stud and adapted to over- 25 hang a walking beam.

2. A device of the class described including an upper bar and a lower bar, flexible means for connecting the upper bar with the lower bar, a walking beam, a 30 flexible member disposed about the walking beam, a stud including a tapered body, a shank at one end and a shouldered shank at the other end, said shouldered shank being engaged with said cable, said tapered 35 body being disposed in the upper bar, a spherical block secured on the threaded shank, a polished rod piercing the lower bar, and a spherical block fixed to the end of the polished rod above the lower bar. 40

In testimony whereof I affix my signature in presence of two witnesses.

WALTER D. GILES.

Witnesses:

ELECTA WADE,
THELMA McALPIN.
